UNITED STATES PATENT OFFICE.

OSCAR E. SHOSTROM, OF SEATTLE, WASHINGTON.

WINDOW LOCK.

Application filed August 25, 1926. Serial No. 131,517.

This invention contemplates the provision of a novel form of window lock, whereby either sash of the window can be locked in either a full closed position, or in any desired opened position, the invention residing in the construction, combination and arrangement of parts as claimed.

In the drawings forming part of this application like numerals of reference indicate similar parts in the several views and wherein:

Figure 1 is a fragmentary front elevation of a window showing one of the sashes locked in a partly opened position.

Figure 2 is an enlarged fragmentary vertical sectional view through the window showing the active position of the lock by full lines and the inactive position thereof by dotted lines.

Figure 3 is an edge elevation of one of the window sashes showing how the lock is arranged thereon.

Figure 4 is a sectional view on line 4—4 of Figure 3.

Figure 5 is a side elevation of one of the pivoted ball receiving members.

Figure 6 is a view taken at a right angle to Figure 5.

Figure 7 is a fragmentary view showing the use of a key for operating the device.

Referring to the drawing in detail 10 indicates a window casing, while 11 and 12 represent the upper and lower sashes, all of which are constructed in the ordinary well known manner. The locking device forming the subject matter of the present invention is identically the same for each sash, so that a detailed description of the invention with one of these sashes will suffice for both. One longitudinal edge of each sash is recessed as clearly indicated at 13 in Figure 2 to accommodate the locking device therefor.

The locking device comprises two pawl receiving members of the character illustrated in Figures 5 and 6, these members being arranged one above the other within the recess 13 as illustrated in Figure 3. These members are indicated at 14 and 15 respectively, and each is in the nature of a trough-like casing open at its front and having its rear wall curved as clearly illustrated in Figure 2. Each member is hingedly mounted within the recess 13, being hingedly connected with an attaching plate 16 which is suitably secured to the

adjacent longitudinal edge of the sash. Projecting from the other end of each member is an extension 17, and as clearly illustrated in Figure 2 these extensions are arranged in overlapping relation and are normally held against an abutment 18 formed on the window casing. Arranged in each member is a ball 19 which when the members are in their normal positions as shown by full lines in Figure 2, are held against the window casing 10, to prevent the window sash from being either raised or lowered, thereby holding the window sash either in a fully closed or in any given opened position.

For the purpose of holding the members 14 and 15 in their locked positions, I preferably make use of a shaft 20 which is journaled in suitable bushings or bearings 21 arranged within the sash as clearly illustrated in Figure 4. Carried by the shaft 20 is an eccentric 22, which in one position of the shaft, engages the overlapped extremities or extensions of the respective members, holding the parts in the position illustrated by full lines in Figure 2. In this position of parts the sash is held immovable with relation to the window casing. When it is desired to release the window sash so that it can be either raised or lowered, it is only necessary to rotate the shaft 20 to move the eccentric 22 to the position indicated by dotted lines in Figure 2, thereby allowing the members 14 and 15 to move to the positions illustrated in dotted lines in the same figure. Any suitable means may be employed for rotating the shaft 20, I having shown in Figure 4 a knob 23 for this purpose, while in Figure 7 I have illustrated the manner of using a key 25, so that the shaft 20 can not be actuated by anyone except the one in possession of the key 25. The members 14 and 15 are identical in construction except that the member 14 is provided with a slot normally closed by a pivoted finger 26, one end of which is provided with an eye 27 connected with the adjacent end of a spring 28, the other end of the spring being connected with an eye 29 carried by the eccentric 22. Consequently when the eccentric is shifted to the position shown by dotted lines in Figure 2, to release the window for movement, the finger 26 is swung upon its pivot by the spring 28, thereby causing the finger to assume a position to support the adjacent ball

19 in the upper or larger end of the member
14.

While it is believed that from the foregoing description, the nature and advantages 5 of the invention will be readily apparent, I desire to have it understood, that I do not limit myself to what is herein shown and described and that such changes may be resorted to when desired as fall within the 10 scope of what is claimed.

What is claimed is:

1. A window lock comprising a pair of pivoted trough-like members arranged within a recess formed in one side of the window sash, extensions formed on the adjacent ends of said members and arranged in overlapping relation, a ball movable within each member and adapted to engage the window casing for holding the sash immovable when said members are in active positions, and means operable from the exterior of the sash for holding said members in their active 20 positions.

2. A window lock comprising upper and lower trough-like members mounted for pivotal movement in a recess formed in the window sash, extensions formed on the adjacent ends of said members and arranged in overlapped relation, a ball movable within each member and arranged to engage the window casing to hold the sash fixed relatively thereto when said members are in their active positions, means operable exterior of the window sash for moving and holding said members in their active positions, or permitting said members to assume inactive positions, and means operable by the last mentioned means for supporting the ball adjacent one end of the upper mem- 30 35

ber when the latter assumes its inactive 40 position.

3. A window lock comprising upper and lower trough-like members pivotally mounted within a recess formed in the window sash, extensions formed on the adjacent ends of 45 said members and arranged in overlapping relation, a ball operable within each member and arranged to engage the window casing for holding the sash fixed relatively thereto, when said members are in their active positions, a shaft journaled in the sash, an eccentric carried by the shaft and cooperating with the overlapped extremities of said members for holding the latter in their active 50 positions or permitting said members to assume inactive positions, and means for operating the shaft.

4. A window lock comprising upper and lower trough-like members pivotally mounted within a recess formed in the window sash, and having their adjacent extremities arranged in overlapping relation, a ball operable in each member and adapted to engage the window casing to hold the sash fixed relatively thereto, a shaft journaled in the 60 sash, an eccentric carried by the shaft and cooperating with the overlapped extremities of said members for moving the latter into their active positions, or permitting said members to assume inactive positions, means for operating said shaft, a pivoted finger mounted on the uppermost member, and means actuated from said eccentric for positioning said finger to support the adjacent ball when said member assumes its 65 70 75 inactive position.

In testimony whereof I affix my signature.
OSCAR E. SHOSTROM.
